UNITED STATES PATENT OFFICE

99,916

DESIGN FOR A BOTTLE OR SIMILAR ARTICLE

Frasier Smith, Wheeling, W. Va., assignor to
Hazel-Atlas Glass Company, Wheeling, W. Va.,
a corporation of West Virginia

Application January 3, 1935, Serial No. 54,709

Term of patent 14 years

To whom it may concern:

Be it known that I, Frasier Smith, a citizen of the United States, residing at Wheeling, in the county of Ohio and State of West Virginia, have invented a new, original, and ornamental Design for a Bottle or Similar Article, of which the following is a specification, reference being had to the accompanying drawing, forming part thereof.

The figure is a front elevational view of a bottle showing my new design.

The building block effect extends entirely around the surface of the bottle.

I claim:

The ornamental design for a bottle or similar article, as shown and described.

FRASIER SMITH.
